(No Model.)

J. D. BILLINGS.
MACHINE FOR FORMING CLIPS ON HORSESHOES.

No. 443,893.

Patented Dec. 30, 1890.

UNITED STATES PATENT OFFICE.

JOHN D. BILLINGS, OF NEW YORK, N. Y.

MACHINE FOR FORMING CLIPS ON HORSESHOES.

SPECIFICATION forming part of Letters Patent No. 443,893, dated December 30, 1890.

Application filed July 10, 1890. Serial No. 358,360. (No model.)

To all whom it may concern:

Be it known that I, JOHN D. BILLINGS, of the city, county, and State of New York, have invented certain new and useful Improvements 5 in Machinery for Forming Clips on Horse and Mule Shoes; and I do hereby declare that the following is a full, clear, and exact description of the invention, which will enable others skilled in the art to which it appertains to make 10 and use the same, reference being had to the accompanying drawings, and to the letters of reference marked thereon, which form a part of this specification.

My object and purpose in this invention are 15 to produce a practical machine which shall by its differently-constructed parts when combined and working together make, form, and shape a "clip" of the proper and required size upon the extreme toe end of horse and 20 mule shoes.

The utility, novelty, and advantages of this invention over the old and present devices and means employed for making or forming out clips upon horse and mule shoes are as 25 follows: Instead of heating the shoe after it is bent into shoe shape and then placing it upon the anvil and by the use of the hand and a blacksmith's hammer making the said clip, or after the shoe is bent and heated at the toe 30 then placing it into a die and stamping it out by repeated blows of a "drop die-hammer" worked by complicated and costly machinery, (and when the clip is made by these two processes named it has cost too much in time, labor, 35 and money, and the clips cannot and have not been made or formed of the exact size, shape, and contour required, and which are so important and necessary an appendage to a horse and mule shoe,) I form the clip by placing 40 the shoe after it is first rolled or formed into shoe-blank bars by my invention and machine made for that purpose, patented March 4, 1890, and No. 422,564, and the said blank bars are then bent into horseshoe shape by

45 my invention and machine patented December 25, 1877, and No. 198,443, and while it is still hot into the shoe-holder of this machine, where it is firmly held on all sides and at the ends, while the hammer is pressed down when 50 the die attached to the end of the hammer comes in contact with the iron on the extreme toe end of the shoe or bead around the out-

side of the shoe and rolled there out of the blank bar, and which bead is for the purposes set forth in my invention and patent issued 55 on an improved horseshoe, dated December 20, 1887, and No. 374,924, and presses the said bead between the said upper die attached to the hammer and the lower die attached to the end of the shoe-holder, thus forming the 60 exact shaped clip desired.

The clip is made of sufficient size and strength to come over and cover the point of the extreme toe-hoof of the foot and should be about three-fourths of an inch long, one-half of an inch high, and from one-eighth of an inch thick at the base to one thirty-second of an inch at the extreme top. This clip when so formed or made on the shoe prevents 65 the shoe when worn on the feet of the animal 70 from crowding or pressing back from the toe of the hoof to the heels and loosening the shoe and from drawing the nails which fasten on the shoe into the inner lining of the hoof, and causing the animal to favor his feet and 75 from lameness.

These clips have been made and used on horseshoes for over a hundred years in this country, and horses and mules cannot be used 80 upon stony pavements, horse-railroads, omnibus, stage-lines, macadamized, and hard country roads without the clip on the shoes. Hence it is a very important and necessary appendage to the horse and mule shoe.

The machine is worked when completed 85 and ready for use by placing it into the space or throat of a common power-press, and which have been long in public use in machine-shops, and is operated by steam or hand power or by any other suitable lever or press 90 device, and will not require more than one-fourth of a horse-power to operate it.

By this improvement and process clips upon horse and mule shoes are made of any size or shape desired, and rapidly, cheaply, 95 and perfectly.

My invention consists of a shoe-holder with its combined mechanisms for holding firmly the shoe while the necessary clip is being formed at the extreme toe end of the shoe, 100 which holder may be made of cast-iron or any other suitable metal that can be cast into the form required; also, of a hammer, one end of which is attached to the shoe-holder, the

other end moving upward and downward and holding the upper die, and which operates the upper die, which by its operation, together with the lower die, dies out or forms the said 5 clip on the shoe, which hammer is also made from cast-iron or other suitable metal that can be used for casting; also, of two dies, the upper and lower die, which are so formed and shaped that when put into their proper 10 places they will by a combined operation of the invention and machine form or make the said clip and are made from tool-steel or other suitable metal.

In the drawings, Figure 1 represents the 15 base and inside of the shoe-holder with its mechanisms for holding the shoe when being clipped. Fig. 2, represents the hammer used for operating the upper die and its attachment at one end of the shoe-holder, together 20 with the shoe-holder, and in which is placed a shoe ready for the formation of the clip. Fig. 3 represents the completed improved machine for forming clips on horse and mule shoes, also showing a completed operation 25 and the clip formed on the shoe. Fig. 4 represents one side or half of a shoe with a section of the iron or bead before the clip is made or formed. Fig. 5 represents one side or half of the shoe after the clip has been formed. 30 Fig. 6 represents a horseshoe with the foot-rest downward and the calks upward, ready and in the right position and form to be placed into the shoe-holder and then form the clip.

35 The letter of reference A shows the solid parts of the inside of the shoe-holder.

A' is that portion which the shoe encircles and against which at the outer end the inside toe end of the shoe is placed, and which 40 prevents the shoe from moving backward or inwardly and holds the shoe firmly when the dies E and F are operating on the toe of the shoe and forming the clip. B indicates the space or shoe-rest into which the shoe is 45 placed and there held firmly until the clip is formed. This space or shoe-rest is made when the shoe-holder is molded and cast, and by a "core," or is "cored out," the rest part of the shoe-holder being made solid. This 50 space or shoe-rest can be made or cast in varied sizes and shapes to take in different shapes and sizes of horse and mule shoes.

CC indicate the steel pinion which attaches one end of the hammer D to the shoe-holder, 55 which works loosely, allowing the upper end of the hammer D to operate the die E.

D D indicate the hammer attached to the shoe-holder, (shown in Fig. 2,) and operates the upper die E. (Shown in Figs. 2 and 3.)

60 E shows the upper die attached to the hammer D. The upper portion of this die is rounded and slides into a hole or boring made in the hammer D, with a shoulder to fit against the lower end side of the hammer and 65 kept firmly in its place by a set-screw b b. The particular lower inside portion of this die, and which is employed in forming the

clip, is shaped concave and of the size required, and the lower die F F is slotted and shouldered into the lower front end of the 70 shoe-holder and held firmly by a set-screw b, the upper end front surface of which is shaped or formed convex. Upon the upper end of this latter die rests the bead C or iron at the toe end of the shoe when the shoe is placed 75 into the shoe-holder, and the hammer D presses down the die E. The bead C or iron at the toe of the shoe is carried by this latter die between it and the die F, forming the clip and leaving it or shaping it convex on the 80 side where the concaved upper die pressed it and concaved on the side where the convexed lower die pressed or shaped it, thus leaving the inside of the clip hollowed out and adapting itself to the exact contour of 85 the toe end of the hoof and forming a perfectly-completed fitting clip of both the inside and outside surfaces.

The letters a a indicate in Fig. 1 the set-screws which are used to keep the heels of 90 the shoes from springing or spreading when the dies are forming the clip. These set-screws are placed in the shoe-holder more as a preventive and precaution than as a necessity.

The letters d d indicate the exact point of 95 the bead at the toe end of the shoe when it is in its place resting on the outer end of the shoe-holder and the point where the upper die E commences to operate the clip.

The operation is as follows: The shoe after being ready, as shown in Fig. 6, and the toe end heated to a red heat, is placed into the shoe-holder, Fig. 1, in the space or shoe-rest B B, and the machine being first placed into 105 the throat of the power-press, the foot is thus placed on the treadle of the power-press and pressed down. This movement causes the clutch attached to the press to operate the movable portion of the press, and which works 110 downwardly to come in contact with the end of the hammer D, bringing the said hammer down the required distance and bringing the two dies E and F together with the iron or 115 bead at the toe end of the shoe between them, and thus forming the said clip. The foot is then taken off from the treadle, and the upper part or movable die of the press goes back to its former place and carries the hammer D with it, the hammer being attached at the 120 upper movable end to the movable press-die by a link or short chain or any other suitable device, and the clipped shoe is then taken out of the shoe-holder by tongs and the operation is ready to be repeated.

125 What I claim as novel and useful, and desire to protect by Letters Patent of the United States, is—

1. A machine for forming clips on horse and mule shoes, consisting of a "shoe-holder," 130 as shown in Figs. 1 and 3, for the purpose and substantially as described.

2. The shoe-holder with the space cored out or shoe-rest B B, the closed or solid por-

tions A A A', and the "open toe-space" d d at the extreme toe end of the shoe, substantially as and for the purposes described.

3. The shoe-holder, as shown in Fig. 2, with the space cored out or shoe-rest B B, the closed or solid portions A A A', the open toe-space d d at the extreme toe end of the shoe, and the lower die F, its outside or surface front of convex form d, shouldered in and held firmly by set-screw b' and b², substantially as and for the purposes described.

4. The hammer D, as shown in Figs. 2 and 3, attached at the lower movable end to the said shoe-holder by pinion C, and the space b³ for receiving and the set-screw b' and b² for holding firmly the upper die E, as and for the purposes described.

5. The hammer D, as shown in Figs. 2 and 3, attached at the lower movable end to the said shoe-holder by pinion C, the space b³ for receiving and the set-screw b' and b² for holding firmly the upper die E, and the upper die E, its inside working-face concaved in form, as and for the purposes described.

6. The shoe-holder, as shown in Figs. 1 and 25 3, with the cored-out space or shoe-rest B B, the closed or solid portions A A A', the open toe-space d d at the extreme toe end of the shoe, and the lower die F, its outside or surface front of convex form d, shouldered in and held firmly by set-screw b' and b², in combination with the hammer D, as shown in Figs. 2 and 3, attached at the lower movable end to the said shoe-holder by pinion C, the space b³ for receiving and the set-screw b' and b² for holding firmly the upper die E, and the upper die E, its inside working surface concaved in form, as and for the purposes described.

In testimony that I claim the foregoing as my own invention I affix my signature in 40 presence of two witnesses.

JOHN D. BILLINGS.
